UNITED STATES PATENT OFFICE.

WILLIAM H. LUCE, OF PRAIRIE CENTRE, ILLINOIS.

CULTIVATOR.

SPECIFICATION forming part of Letters Patent No. 269,689, dated December 26, 1882.

Application filed September 4, 1882. (No model.)

To all whom it may concern:

Be it known that I, WILLIAM H. LUCE, of Prairie Centre, in the county of La Salle and State of Illinois, have invented a new and Improved Cultivator, of which the following is a full, clear, and exact description.

My invention consists of improvements in the construction and arrangement of the wheel-gear, hitching attachments, and adjusting devices of cultivators, for operation as herein-after fully described.

Reference is to be had to the accompanying drawings, forming part of this specification, in which similar letters of reference indicate 15 corresponding parts in all the figures.

Figure 1 is a perspective view of my improved cultivator. Fig. 2 is a front elevation with the tongue in cross-section. Fig. 3 is a section of one of the wheels, showing the construction of the same; and Fig. 4 is a broken perspective view of a plow with its attaching device.

The frame consists of the front cross-beam, *a*, to which the tongue *b* is pivotally attached, 25 the side beams, *c*, extending rearward therefrom, wheel-standards *d*, braces *f*, and the connecting-bar *e* of the wheel-standards. Caster-wheels consisting of metal rim *g*, with the spokes *h* riveted in and hub *i* cast on the spokes, are 30 swiveled on the lower ends of these standards by yokes *j*, the said yokes being arranged horizontally for enabling the standards to extend lower down and the wheels to be larger than if said yokes were vertically arranged over the 35 wheels. The frame being too high for the draft of the horses to be in the usual direct line from it in order to pass over growing crops, the evener *a* is pivoted on the bar *e* to swing vertically, and the hitching-straps *k* are made to 40 extend down along the wheel-standards *d* under guide-rollers *l*, pivoted in the braces *f*, which are made to project beyond the wheel-standards for the purpose. The tongue *b* has an adjustable connecting-bar, *m*, jointed to it at *n* and 45 ranging through the slotted post *o* on the top of cross-bar *e*, to be fastened at any one of its series of holes *p* by the pin *q* to connect said tongue, so as to balance the machine higher or lower on the wheels according to the depth 50 it is required that the plows shall work.

In order to enable the operator to change

the connection of the tongue readily while in his place behind the machine a spring-actuated presser, *t*, arranged in a tubular case, *u*, is made to bear on the shank *v* of the pin *q*, which is pivoted to the front cross-beam, *a*, at *w*, to cause said pin to connect automatically with the bar *m* when its holes register with said pin, and a lever, *x*, is pivoted to the frame at *y*, connected to shank *v* by a rod, *z*, and extended 60 back along one of the side beams, *c*, of the frame to the attendant's position, in order that at any time that he may desire to alter the pitch of the machine he may pull out said pin and raise or depress the hind end of the machine by its 65 handles *a'*, and secure the frame in the new position by releasing the lever *x* and allowing the pin *q* to be sprung into bar *p*.

The plows *b'* are attached to the prongs *c'* of the T-head *d'* of the cranked arms *e'*, fitting in 70 the ends of the tubular shaft *f'* through the side pieces, *c*, and fastened by set-screws *l'*, so that the plows may be shifted toward and from each other to alter their distance apart by moving the arms *e'* lengthwise in the tubular shaft, 75 in which the arms *e'* may also be turned, as desired, to allow the plows to shift forward or backward to some extent to alter their pitch. The T-heads *d'* range in the diagonal line necessary to set the advance plows inside or 80 nearer together than the rear ones for making their respective furrows side by side, and from the front end of each head *d'* a draft-rod, *g'*, extends up to the front beam, to which it is adjustably connected by a socket, *h'*, pin *i'*, 85 and a series of holes, *j'*, in the rod, said rods being arranged in the same oblique lines that the T-heads are for drawing in the line of the plows. Wooden pins are employed to break for the relief of the plows in case they are 90-95 obstructed.

The plows *b'*, Fig. 4, are connected to a bar, *n'*, which I call a "ratchet," by a pin, *o'*, in the plow-blade, and a bolt, *p'*, the pin being changeable from one to another of a series of ratchet-notches *o* in the bar to alter the pitch, and said ratchets are connected to the prongs *c'* by a staple, *m'*.

I propose to arrange the connections of the plows so that they may be changed at will for 100 the application of plows of different kinds and forms according to the work at hand.

Having thus described my invention, what I claim as new, and desire to secure by Letters Patent, is—

1. The combination of tongue *b*, bar *m*, slotted post *o*, spring-pin *q*, and lever *x* with the cultivator-frame mounted on caster-wheels, substantially as described.
2. The plows *b'*, attached to the shanks *c'* of T-heads *d'* of crank-arms *e'* in tubular shaft *f'*, said T-heads being arranged obliquely to the machine and in the line of the plows, substantially as described.
3. The draft-rod *g'*, in combination with plow-shanks *c'*, the crank-arms *e'*, and the ta-

bular shaft *f''*, whereby the plows are adapted to be shifted forward and backward, said rods being adjustably connected to the front beam by sockets *h'* and pins *i*, substantially as described.

4. The combination of the crank-arms *e'*, having the plows attached to them, tubular connecting-shaft *f'*, beams *c*, and the binding-screws *l'*, substantially as described.

WILLIAM H. LUCE.
